UNITED STATES PATENT OFFICE.

RICHARD POPP, OF PARIS, FRANCE.

AUTOMATIC ADVERTISING APPARATUS.

1,073,927.

Specification of Letters Patent. Patented Sept. 23, 1913.

Application filed July 17, 1912. Serial No. 709,908.

To all whom it may concern:

Be it known that I, RICHARD POPP, citizen of the French Republic, residing at Paris, Department of the Seine, in France, have invented certain new and useful Improvements in Automatic Advertising Apparatus; and I do hereby declare the following to be a full, clear, and exact description of the invention, such as will enable others skilled in the art to which it appertains to make and use the same.

The invention relates to an automatic advertising apparatus.

This apparatus comprises a band carrying advertisements which passes over two driving drums and is fixed to two other drums from which it is wound and unwound alternately. These drums are operated by one and the same mechanism, which imparts to the said band an intermittent motion so as to insure the regular succession of the advertisements allowing their reading. In order to produce this intermittent motion the operating mechanism comprises a Maltese cross, which is turned at equal intervals and acts on the drums carrying the band. The apparatus, moreover, comprises a reversing gear which, at the end of the course, reverses the operating mechanism.

In the accompanying drawings: Figure 1 is a front elevation of an apparatus in accordance with the invention. Fig. 2 is a side elevation of such apparatus. Fig. 3 shows a modification of the operating mechanism. Fig. 4 is a plan of the same.

The apparatus is operated by a driving shaft 1 upon which is slidable a sleeve 2 carrying two bevel-wheels 3, 3¹. According to the position of the sleeve 2 one or the other of these bevel wheels meshes with a bevel wheel 4 keyed on the shaft 6. The displacement of the sleeve 2 is effected by means of a fork 7 pivoted at 50. An arm 51 attached to this fork, carries a peg or pin 52 projecting into a groove in a screw nut or traveler 8 on the screw spindle 21. The groove in the traveler forms a shoulder at each end thereof adapted to engage the pin 52. The screw spindle receives its rotation from the shaft 6 by means of the two pinions 22 and 23. The fork 7 is held in each of its end positions by means of a spring 9 which is fastened at one end to the fork and at the other to the frame 10.

On the shaft 6 is keyed a disk 5 carrying a peg or pin 24. This latter engages suc-

cessively the grooves of a Maltese cross 26 firmly connected with a pinion 27 engaging a pinion 28 keyed on the shaft 29 of a drum 12. This shaft 29 operates by means of the bevel-wheels 30 and 31 a shaft 32 which imparts its rotation by means of a suitable bevel-gearing to a drum 12¹ similar to drum 12. The band 19 carrying the advertisements passes over the drums 12 and 12¹ provided with teeth 49 and 49¹ respectively, and the ends of the said band are wound or rolled up on or wound or rolled off from the two drums 11 and 11¹ which are set in motion by means of bevel wheels similar to those operating the drums 12 and 12¹. In order to compensate the variations of diameter of the roll formed by the band on the drums 11 and 11¹, each of these drums is connected with its driving shaft by means of springs 13 and 13¹ respectively.

The working of the apparatus is as follows: The fork 7 being in the position shown in Fig. 1, the main driving shaft 1 rotates by means of the bevel gear 3, 4 the shaft 6. The peg 24 of the disk 5 turns the Maltese cross 26 for a quarter of a circle which corresponds to a certain length of the band. During the same time, owing to the transmission of motion effected by means of the shaft 32, the drums 11, 11¹, 12 and 12¹ rotate in the same direction. As all the drums are operated or driven by the same driving mechanism the band is not submitted or exposed to any undue strain or effort and will therefore not be distended. After the Maltese cross has been turned for 90°, the peg 24 and the cross disengage; the latter and the drums remain at rest, while the former performs an idle course. During the rotation of the shaft 6, the screw spindle 21 is rotated by means of the pinions 22, 23 whereby a lateral motion is imparted to the nut 8. When this nut is near one end of its course one of the shoulders thereon will engage the pin 52 and thereby shift the fork 7. Under the action of the spring 9 the fork 7 is rocked; the bevel wheel 3 is disengaged and the bevel wheel 3¹ thrown into gear with the bevel wheel 4 whereby the rotation of the shaft 6 is reversed. Consequently the direction of motion of the Maltese cross and of the drums 11, 11¹, 12, 12¹ is likewise reversed. The dimensions of the transmission organs or elements are chosen in such a manner that the number of revolutions of the disk 5 effected

in either direction corresponds to the complete unwinding or unrolling of the band 19.

Figs. 3 and 4 illustrate a slightly modified construction of the driving mechanism. 5 The main driving shaft 1 carries, in this instance, an endless thread or worm 25 meshing with a worm wheel 33 which drives by means of a gearing 34, 35, 36 and 37, a crown-wheel 38. Above the latter is arranged 10 a sleeve 41 provided with two pinions 39, 39¹. The said sleeve rotates with its shaft 6 but is capable of being displaced thereon in longitudinal direction. The displacement of the sleeve 41 is effected by 15 means of a fork 42 pivotally jointed at 43 to the frame and at 44 to an arm 45 the free extremity of which is engaged between two pegs or pins 46 fixed to the frame. The arm 45 and the fork 42 are connected by a 20 spring 47 which secures the sleeve 41 in each of its end positions. The fork is displaced by a screw nut 8 mounted on a screw spindle 21, operated as in the construction shown in Figs. 1 and 2, by pinions 22, 23. 25 The transmission of the rotation of the shaft 6 to the drums is effected in the same manner as before.

The apparatus forming the subject matter of the invention affords the advantage that 30 its operation and function is very reliable and its construction simple and economical.

The apparatus may advantageously be used in connection with cabs and carriages in which case the main driving shaft may 35 be operated preferably by the flexible shaft actuated by one of the wheels of the carriage. The apparatus may also be operated by means of a clockwork or any other suitable driving means (electric motor for example).

I claim:

1. An advertising apparatus comprising winding rollers, guide rollers, a web associ-

ated with said winding and guide rollers 45 mechanical connections between the shafts of all of said rollers for driving the same, radially directed arms secured to the shafts of the winding rollers, and springs connecting said winding rollers and said radially directed arms. 50

2. An advertising apparatus comprising winding rollers, guide rollers, a web associated with said winding and guide rollers, means to actuate one of said rollers, direct mechanical connections between the shafts 55 of all of said rollers to actuate the same simultaneously, radially directed arms secured to the shaft of the winding rollers, and springs connecting said winding rollers with said radially directed arms. 60

3. An advertising apparatus comprising winding rollers, guide rollers, mechanical means for driving all of said rollers, a reversing mechanism associated with the driving means comprising a shiftable reversing 65 sleeve, a pivoted lever having connection with said sleeve, means to actuate said lever comprising a worm shaft, a traveler adapted to be shifted longitudinally of and by the worm shaft, said traveler provided with 70 shoulders thereon and said lever adapted to be engaged by said shoulders on the traveler to shift the reversing sleeve, a second lever pivotally connected to said first-named lever and directed away therefrom, 75 means to guide the free end of said second lever, and resilient means connecting the opposite ends of said levers whereby said sleeve is normally held in its extreme shifted position. 80

In testimony whereof I affix my signature, in presence of two witnesses.

RICHARD POPP.
